(57) **CLAIM**

The ornamental design for a glue chip beveled glass privacy window, as shown and described.

DESCRIPTION

FIG. 1 is a front view of my glue chip beveled glass privacy window;

FIG. 2 is a front perspective view of my glue chip beveled glass privacy window;

FIG. 3 is an enlarged side view of one of the panes of the glue chip beveled glass privacy window in triple glazed configuration in a frame, wherein the broken line shows non-beveled glass and the frame which form no part of the claimed design; and,

FIG. 4 is an elevational view of my glue chip beveled glass privacy window in a frame and located in a bath area, wherein the broken lines shows the frame and the bath area which form no part of the claimed design.
